US00D941806S

(12) **United States Design Patent** (10) Patent No.: **US D941,806 S**
(45) Date of Patent: ** Jan. 25, 2022

(54) **EARPHONE**

(71) Applicant: **Chunhong Liu**, Dongguan (CN)

(72) Inventor: **Chunhong Liu**, Dongguan (CN)

(**) Term: **15 Years**

(21) Appl. No.: **29/726,336**

(22) Filed: **Mar. 2, 2020**

(51) LOC (13) Cl. **14-01**

(52) U.S. Cl.

USPC **D14/223**

Andrew C. Cheng

(57) **CLAIM**

The ornamental design for earphone, as shown and described.

DESCRIPTION

FIG. 1 is a perspective view of an earphone showing my new design according to a first embodiment;

FIG. 2 is another perspective view thereof;

FIG. 3 is a front view thereof;
FIG. 4 is a rear view thereof;
FIG. 5 is a right side view thereof;
FIG. 6 is a left side view thereof;
FIG. 7 is a top plan view thereof;
FIG. 8 is a bottom plan view thereof;
FIG. 9 is a perspective view of an earphone showing my new design according to a second embodiment;
FIG. 10 is another perspective view thereof;
FIG. 11 is a front view thereof;
FIG. 12 is a rear view thereof;
FIG. 13 is a right side view thereof;
FIG. 14 is a left side view thereof;
FIG. 15 is a top plan view thereof;
FIG. 16 is a bottom plan view thereof;
FIG. 17 is a perspective view of an earphone showing my new design according to a third embodiment;
FIG. 18 is another perspective view thereof;
FIG. 19 is a front view thereof;
FIG. 20 is a rear view thereof;
FIG. 21 is a right side view thereof;
FIG. 22 is a left side view thereof;
FIG. 23 is a top plan view thereof;
FIG. 24 is a bottom plan view thereof.
FIG. 25 is a perspective view of an earphone showing my new design according to a fourth embodiment;
FIG. 26 is another perspective view thereof;
FIG. 27 is a front view thereof;
FIG. 28 is a rear view thereof;
FIG. 29 is a right side view thereof;
FIG. 30 is a left side view thereof;
FIG. 31 is a top plan view thereof;
FIG. 32 is a bottom plan view thereof.
FIG. 33 is a perspective view of an earphone showing my new design according to a fifth embodiment;
FIG. 34 is another perspective view thereof;
FIG. 35 is a front view thereof;
FIG. 36 is a rear view thereof;
FIG. 37 is a right side view thereof;
FIG. 38 is a left side view thereof;
FIG. 39 is a top plan view thereof; and,
FIG. 40 is a bottom plan view thereof.

(Continued)

The broken lines are for the purpose of illustrating patterns on the earphone of embodiments 1 through 5. The broken lines form no part of the claimed design.

1 Claim, 40 Drawing Sheets
